UNITED STATES PATENT OFFICE.

THEODOR BACHOFEN, OF WESTBROOK, MAINE, ASSIGNOR TO BACHOFEN NOVELTY FABRIC INVENTIONS, INC., A CORPORATION OF NEW JERSEY.

METHOD AND MEANS FOR MAKING PILE FABRICS.

Application filed August 6, 1921, Serial No. 490,352. Renewed February 26, 1927.

My present invention more particularly concerns pile fabrics of the type known as filling velvets, that is, fabrics in which there is a "ground" fabric consisting of the ordinary warp and weft, usually of relatively fine thread, in combination with a supplemental weft or filler which is bound in certain meshes of the warp and is floated over other intervening meshes. In some of the simple types of such fabric, successive filler threads have their float portions arranged in alignment lengthwise of the cloth so as to produce a stripe or corded effect. See for instance the "Bedford cord" shown in Fig. 1 of patent to Migel, 1,333,032, granted March 9, 1920. Heretofore it has been proposed to cut the center of each float portion of each filler, thereby forming a double row of more or less bushy, projecting ends giving the effect of a corduroy velvet.

So far as I am aware, however, such cutting of the float filler has been by means of small, automatic scissors located some two or four inches beyond where the weaving of the cloth has been completed, that is, beyond the point of farthest throw of the reed which pushes or "beats" the successive wefts in the successive meshes of the warp. As fabrics of this type are commonly made of very fine threads running say from forty to two hundred threads per inch, a distance of two to four inches lengthwise of the fabric is, functionally considered, a long distance. By the time the fabric has traveled this distance beyond the final weaving point, the transverse tension which is imposed on the wefts by the reed is entirely relieved and the cloth shrinks, that is, narrows to a considerable and more or less variable extent. Hence it is very difficult to locate the scissors so that they will cut evenly at the centers of the respective floats constituting the lengthwise cord effect.

Hence one object of my invention is to produce a superior and more uniform cutting operation whereby each float thread may be cut at the exact point desired, either at the precise center to produce a regular corduroy effect, or, if desired, nearer one side than the other so as to produce alternately longer and shorter piles, giving the effect

of alternately large and small striped corduroy. To this end I arrange matters so that the cutting operation is performed at or very near the time when and place where the weft is beaten up in the warp at the end of the forward stroke of the reed.

Another object in my invention is to interpose a simple knife edge in the path of the float at the exit end of the machine against which the float will automatically progress in its travel through the machine. Preferably this knife edge is located behind the point of farthest forward travel of the reed, so that, in its extreme forward position, the reed stretches and presses the float against the cutting edge, thereby severing the float at the desired point, at the very instant it is fully tensioned and in its final position in the mesh of the warp.

Preferably each knife edge is formed on and projects from the upper edge of a long thin steel blade. These blades normally lie parallel between the lowermost set of warp threads, that is to say, just above the level of the lay where the shuttle shoots across to lay the weft. The shuttle traveling above this level, lays the filler crosswise on the smooth upper edges of the blades; then the reed slides the filler along said upper edges until the filler encounters the projecting knife edge and is severed. Adjacent reeds on either side of the cutting edge are preferably spaced apart far enough so that if, by any chance the float is not completely severed on the first beat of the reed, any undivided fibres will surely be severed on the next beat of the reed, and, at no time will there be any danger of pinching of said fibres, as where scissors are used.

While it would be possible to arrange matters so that the knives would remain fixed in the position above described, one shuttle laying a ground weft below the blades and the other laying a float filler weft above the blades, I prefer to have the ground weft shuttle and the supplemental or filler weft shuttle traverse the same path alternately. Hence another feature of my invention is to provide a supplemental harness to which the rear ends of the blades are connected so that they may be lifted above the level of

the uppermost warp threads during the "ground pick", or, more generally stated, during the time when the shuttle is being shot across the lay warp to lay a weft which it is desired to have remain uncut. Of course, the "dobby jack" for lifting this harness may be arranged to operate at any time desired and it is thus possible to arrange to lay certain picks of the "filler" weft below 5 the cutter blade so that certain floats will be uncut while others are cut, thus making it possible to produce a great variety of patterns.

The raising and lowering of the blade 10 harness, as also the warp harness, may be predetermined or controlled in any desired way either for producing regular effects, as in the so-called "shaft" loom, or for producing any desired pictured or ornamental 15 effects, as in the Jacquard loom, where, the harnesses being controlled by a pattern, the variations are almost unlimited.

In the particular embodiment illustrated in the drawing all of the blades are connected to the heddles of a single harness, but obviously the number of harness shafts for the blades may be multiplied to any desired extent, after the same manner that warp 20 harnesses are commonly multiplied, according as the desired patterns are more intricate or variegated.

Another feature of my invention involves utilizing the spaces between the blade elements constituting the reed, as guides for 25 keeping the cutter blades upright and parallel with each other and with the warp.

The blades are preferably long strips of very thin spring steel. They are preferably quite narrow, and, when the blade is in the lowered position, they are substantially horizontal. The upper smooth edges are preferably lowest at or near the point where the shuttle travels over them and preferably they incline upward from said point for a distance 30 approximately equal to the throw or "beat" of the reed. Hence when a supplemental weft or filler is laid over them and is pushed forward by the reed, the float portion is gradually stretched upward away from the ground portion of the fabric, thereby increasing its tension at the point where the reed presses it against the steep upward incline of the cutting blade. The smooth upper edge of the blade on which the weft 35 slides forward curves into the steeper cutting edge without forming any notches or angles in which fibres of the weft could be caught.

The above and other features of my invention may be more fully understood from the following description in connection with the accompanying drawings in which the views, so far as concerns the ordinary loom mechanism, are more or less diagrammatic, the full illustration being confined to my cutter

attachment, the reed which cooperates therewith to effect the cutting, and the fabric to be cut. In these drawings,

Figure 1 is a diagrammatic plan of fabric in a loom indicating how it narrows after 70 leaving the reed, and where the cutting is performed in accordance with my present invention, as contrasted with the location of prior cutting devices.

Figure 2 is a top plan view showing the 75 fabric on a very large scale and with the weave opened up so that the relations of the threads and my weft cutting attachment can be easily observed.

Figure 3 is a side elevation of one of my 80 weft cutter blades.

Figure 4 is an enlarged, more or less distorted, section showing the ground fabric and the severed float, the section being transversely of the warp and parallel with the 85 weft.

Figure 5 is a similar view of the fabric taken parallel with the warp and at right angles with the weft at the point where the ground weft and the supplemental weft are 90 bound together in pairs in the mesh of the warp.

Figure 6 is a vertical section parallel with the warp, showing my weft float cutter in the elevated, inoperative position and the parts 95 of a loom which directly cooperate therewith.

Figure 7 is a similar view of the cutter in lowered, operative position.

Figure 8 is a similar view on a larger 100 scale showing the cutter in operative position and the reed at the forward point of its stroke at the instant when the float filler is to be severed.

Figure 9 is a similar view on a still larger 105 scale showing the reed at an instant when the float is partially severed.

Fig. 10 shows a modified weave.

In Fig. 1 I have indicated in a primitive way the relations of the unwoven portion of the warp threads in the rear of the reed A, the weaving line B-B on which the fabric is transversely stretched by the reed A, and the gradual narrowing of the woven fabric to where this tension is wholly relieved, as at C-C.

As is well known in the art, the parallel warp threads are wound on a supply drum called the warp beam (not shown) and the finished fabric is wound up by a power driven take-up roll at the front of the machine (not shown). The warp beam, that is the supply roll, has a friction drag on it so that the warp threads are kept under a considerable tension due to the pull of the take-up roll which pulls them through the loom. The roll from which the warp threads are drawn and reed A, which guides said warp threads, are both substantially wider than the take-up roll which draws them so that the individual unwoven warp threads are 125 130 135

held substantially parallel up to the forward face B—B of the reed A, and all the convergence is localized beyond said line B—B, where the fabric gets farther and farther away from the spreading effect of reed A.

This indicates in a general way the advantage of my attachment which operates to sever the float threads along the line B—B, where the widthwise distances are positively fixed by the reed, as contrasted with the prior scissor devices which are located at or below the line C—C where the fabric is not held to a fixed width and the widthwise locations of the floats are therefore more or less uncertain.

As is well known, the reed is a rigid structure comprising a large number of slightly separated thin steel blades or "dents" which form partitions to guide the warp threads 20 and push or "beat" the weft threads up into the open V-shaped "shed" between the upper and lower sets of warp threads to form a closely woven fabric. In the present case the reed is of the so-called "corrugated" type comprising pairs of relatively long (wide) dents 1, 2, the forward edges of which extend ahead of the intermediate shorter dents 3, 4.

In Fig. 2, I have shown a greatly magnified view of the small portion of fabric included between two pairs of long dents 1, 2—1, 2, and one pair of intermediate short dents 3, 4 with my weft cutter 5 located in operative relation to the float, midway between the intermediate short dents.

In the fabric selected for illustration in Fig. 2, there is a continuous uniform weave constituting the "ground" comprising the usual warp threads woven alternately above and below the successive weft or "binder" threads of the weft. The binder threads are laid by the shuttle at a time when alternate warp threads are elevated and intervening threads depressed to form the open V-shaped shed. The warp threads may be distinguished by their function. As shown in the drawings, the binder warp threads 7^a, 7^a have been depressed and the cooperating threads 7^b, 7^b have been elevated to form the V-shaped shed in which the filler 9 has been laid by the shuttle. On the preceding stroke of the loom the alternate ground warp threads 8^a, 8^a had also been depressed to parallelism with the binder warp threads 7^a and the alternate ground warp threads 8^b, 8^b had been elevated to parallelism with binder warp threads 7^b, 7^b, thereby forming a complete shed entirely across the loom in which the binder or ground weft thread 10 was laid. As a result the ground weft thread 10 is bound by all of the warp threads, while the filler thread 9^a is bound in only by warp threads 7^a, 7^b, leaving the intermediate portion as a "float" passing above, and free from, the underlying ground fabric.

Obviously the same procedure had already been gone through with reference to filler thread 9^a and ground weft 10^a, except that the warp threads just described as elevated are the ones which were previously depressed, 70 and vice versa.

Fig. 4 shows the relations of the threads of the ground and float wefts with respect to the warp threads 7^a, 7^b, 8^a, 8^b, while Fig. 5 shows the interweaving of the warp threads 7^a, 7^b, to bind in pairs, a filler weft 9 with a ground weft 10 in the same mesh of the warp.

In these operations, it will be evident that blade 5 was elevated to an inoperative position, so that the ground weft 10 was laid under it and did not encounter the knife edge when pushed to position by the forward stroke of the dents 1, 2, 3, 4, of reed A. It is equally evident that blade 5 was subsequently depressed so that the filler weft 9 was laid over it and did encounter the knife and was severed by it, when pushed against it by the reed. The blade 5 and the means for operating the parts to perform the above operations, are further indicated in the other figures of the drawings.

The blade 5 is of fine quality spring steel capable of taking a good cutting edge, and is thin as practicable, so as to be of minimum weight and occupying as little space as possible between the warp threads, while, at the same time, having the requisite strength. For the shape shown in Fig. 3, the thickness may be say one to two hundredths of an inch. The blade is of substantial vertical width at the ends 5—5^a, but the intermediate portion which passes through and engages the dents of the reed are narrowed down as much as possible, the narrowest point being in the region 5^b, 5^c, so as to afford the least possible obstruction to the passage of the shuttle over the blade when the latter is in the lowered operative position.

From 5^c the blade widens upwardly to the base of knife 6 so that the overlying float will be stretched away from the underlying ground fabric, by the time the float reaches the blade 6. The blade 6 preferably projects a substantial distance 100 above the upper edge of the blade so that it will afford a reasonable surplus of metal to be used up in resharpening operations. The rearwardly directed cutting edge of the knife is slightly inclined so that the float, 110 tensioned and pressed forward by the reed, will be subjected to a draw cut. As will be evident from Fig. 2 the nearest reed dents 3, 4, are so far away that said cut is essentially a slitting knife action as distinguished 115 from a shearing or scissors cut.

At the forward end where the knife is nearest the fabric it is preferably bevelled off, as at 5^d, to avoid catching in the fabric. The forward end of the blade is provided 120

with an eye 5^e, whereby, as shown in Figs. 6 to 9 inclusive, the blade is pivotally mounted on a crossbar or wire 11, which is non-positively held in position on the fabric by a series of light depressing springs 12, to prevent jumping, and a series of light retracting springs 13 arranged to apply a slight forward tension. Springs 12, 13, are anchored to crossbar 14. The blade is provided at the other end with another opening 5^f, which engages pivot 15 on a vertically slideable harness heddle 16. This, being a rather flexible tension-member, is braced against forward stresses by means of suitably spaced stationary guides, 17^a, 17^b, 17^c, and 17^d. Intermediate the ends, the blade extends through the reed A between two of the short blades or dents 3, 4, which serve to steady and guide the same. The blade is further guided by a reed comb D of smaller size but of similar construction, which extends across the loom.

This reed comb is bridged across the fabric as indicated in Figs. 8 and 9, and is supported in fixed position by or upon the side frames of the loom. It limits the downward movement of the blades under the pressure of spring 12.

In this connection it is to be explained that the entire distance between the binding points of the float in Fig. 2 may be only about $\frac{1}{5}$ of an inch or less when measured on fabric woven of threads of minute sizes commonly used for this purpose, and it will be understood that there are as many blades 5 as there are rows of floats which it is desired to have severed thereby.

Referring to Figs. 6 and 7, it will be evident that the cutter blade may be rendered inactive by lifting the harness "shaft" 17 and heddle 16 to the position shown in Fig. 6, where the shuttle S which lays the ground weft 10, or shuttle S' which lays the filler weft, will pass under it; also that when the harness is depressed to bring the knife in position shown in Fig. 7, the shuttle will pass over it and will lay a weft which will be cut by the knife 6 as soon as the shuttle gets out of the way and the reed A is swung forward to the position shown in Figs. 8 and 9.

In the particular arrangement shown in the drawings where the purpose is to sever all of the float portions, it is obvious that the harness 16, 17, will be lifted to render the knives 5 inoperative during every stroke of the ground weft shuttle S and will be depressed during every stroke of the filler shuttle S'. Obviously, however, the elevating and depressing of the blade may be governed in any desired way to produce any desired effect, a simple variation being to have the knife depressed to the operative position only during the laying of every second, third or fourth float, thus having any

desired number of uncut floats alternating with any desired number of cut floats. As before stated, looms of this type intended to produce variegated effects may have any desired number of sets of harness controlled separately or together having any number of desired sets of warp threads controlled thereby; and similarly there may be any number of sets of harness to control any number of desired sets of float cutting blades so that the cuts may be variegated across the width of the fabric as well as lengthwise thereof.

The harnesses for the previously described sets of warp threads I have shown in Figs. 6 to 8, harness shaft 18 controls all the binder warp threads 7^b these being threaded through the eyes of the heddles 18^a, the latter being in the same plane and therefore appearing as one. Harness shaft 19 controls all the binder warp threads 7^a, threaded through the eyes of parallel heddles 19^a. As the warp threads 7^a and 7^b are in cooperating pairs, the binder shafts 18 and 19 cooperate correlative, and, in the particular pattern shown, they reverse position one being up and the other down alternately.

The ground warp harnesses are similarly arranged in pairs 20, 21 and 22, 23; 20 being up when 21 is down, and 22 up when 23 is down, to form the complete shed comprising all ground warp as well as the binder warp during the passage of the ground weft shuttle S; and all four shafts 20, 21, 22, 23, being down out of the way at the time the float pick of shuttle S' lays the float weft 9. As before explained there may be as many harness sets and as many shafts in each set as may be necessary to produce the desired complexity of pattern.

With the above explanation it would be evident that Fig. 6 shows the position of parts when the knife is in the elevated position. In such position it will be noted that the knife is parallel with, and above, the upper layer or shed of warp thread. As shown, the ground warp threads 8^b and 8^b, as well as the binder warp threads 7^b, 7^b, are in the uppermost position and the reed A is upright in the rearward position, held there by the lay 24, the upper surface of which forms the support for the shuttle S as it is shot across by the usual picker stick (not shown), in the usual manner, to lay the binder weft 10. Then, as shown in Fig. 7, elevated ground shafts 20, 22 and also the knife shaft 17, are lowered, and only the warp threads 7^a are elevated while the shuttle S' lays the float weft 9.

The shuttle S', having completed its pick and being in the shuttle box beyond the lay 24, the latter moves forward carrying with it the reed A, which pushes the filler weft 9 forward along the smooth tops of the blades, tensioning the filler and forcing it against

the knife edge 6, as above described and as is shown in Figs. 8 and 9.

To make the fabric shown in Fig. 2 the above cycle of operations is repeated as often as desired.

It will be obvious that any desired sizes, colors, and materials may be employed for the ground weft and the same or any different sizes, colors and materials for the filler weft; also that any of the warp threads may be independently varied as to color, sizes and materials; and that the vast variety of variations in these respects may be combined with any of the previously described variations in locations and in the numbers of floats that are uncut or that are cut.

The threads which may be used for either warp or weft may be of almost any known structure of single filaments of fibre, wire, or other, up to any desired number of assembled filaments or fibres and the assembled fibres may be entirely untwisted, slightly twisted, moderately twisted, or may be of extreme high twist, as in crepe, and the material may be anything known or desired, including cotton, linen, wool, silk, artificial silk, and metallic wires or filaments of all kinds.

While the particular fabric illustrated shows the "filler" weft as bound in by two pairs of warp threads and floated over sixteen pairs of warp threads, it is obvious that the numbers of the threads in each instance may be varied to any desired extent and the term filler used herein is intended to cover all said variations, even down to the particular case where there is a knife blade for each and every pair of warp threads. It will be evident, however, to those skilled in the art that in this extreme case, the pile produced is not likely to be very firmly secured in the ground fabric unless some special precautions are taken, either as to the weaving or as to further securing the pile before it is put to use. For ordinary purposes, it will be found that three, and preferably four, binder warps between slitting knives will be practically the minimum and in most cases the float should be over two or more warp threads rather than one.

An illustrative example of fabric with very short float is shown in Fig. 10 where

there is one float with blade 5 thereunder, for every three pairs of warp threads. 55

I claim:

1. An attachment for looms having the usual harness, reed and shuttle, said attachment comprising a set of long, thin blades, a special harness in the rear of the reed to 60 which said blades are attached, said blades extending through the reed parallel with the warp threads and terminating a suitable distance beyond the weaving point whereby said blades may be raised and lowered in 65 approximate parallelism with any desired set of warp threads; said blades being provided with upwardly projecting, rearwardly directed cutting edges normally positioned near the point of farthest forward throw 70 of the reed and held stationary in such position during the forward stroke of the reed; together with the further feature of means for permitting backward and forward movement of the forward ends of the blades when 75 the harness is raised, said means including a transverse member associated with the blade, means for guiding the same parallel with the fabric and a retracting spring to assist in drawing the blade forward when 80 the harness is lowered.

2. An attachment for looms having the usual harness, reed and shuttle, said attachment comprising a set of long, thin blades, a special harness in the rear of the reed to 85 which said blades are attached, said blades extending through the reed parallel with the warp threads and terminating a suitable distance beyond the weaving point whereby said blades may be raised and lowered in 90 approximate parallelism with any desired set of warp threads; said blades being provided with upwardly projecting, rearwardly directed cutting edges normally positioned near the point of farthest forward 95 throw of the reed and held stationary in such position during the forward stroke of the reed; together with the further feature of a reed comb for guiding and maintaining parallelism of the forward ends of all the 100 blades.

Signed at New York, in the county of New York and State of New York, this 5th day of August, A. D. 1921.

THEODOR BACHOFEN.
